UNITED STATES PATENT OFFICE.

WILLIAM MILLARD, OF NEW YORK, N. Y.

DISPENSING APPARATUS.

1,157,645.

Specification of Letters Patent. Patented Oct. 19, 1915.

Application filed December 23, 1909. Serial No. 524,703.

To all whom it may concern:

Be it known that I, WILLIAM MILLARD, a subject of the King of Great Britain, residing at New York, borough of Manhattan, in 5 the county and State of New York, have invented a new and useful Dispensing Apparatus, of which the following is a specification.

This invention concerns means for the dispensing of such articles as cups, its chief 10 objects being to provide a simple, compact and effective apparatus for this purpose.

The invention consists in the features and 15 combinations hereinafter described and particularly pointed out in the claims.

In the accompanying drawings, Figure 1 is a front elevation of one embodiment of my improved dispensing apparatus; Fig. 2 is a side elevation thereof, looking from the 20 right in Fig. 1; Fig. 3 is an elevation of the opposite side of the apparatus, parts being broken away and in section; Figs. 4 and 5 are details in side elevation especially illustrating in two positions the mechanism for 25 controlling the delivery; Figs. 6 and 7 are horizontal sections on the lines 6 and 7, respectively, of Fig. 4, and Fig. 8 is a vertical sectional detail on the line 8 of Fig. 7.

Like elements are designated by similar 30 characters of reference throughout the various views.

I have illustrated a casing A having a vertical rear wall 10, opposite parallel side walls 11, 11, a front wall 12 inclined upwardly, converging toward the rear wall, and a semi-cylindrical protuberance 13 extending for practically the entire length of the front wall. From the lower portion of the casing is a forward extension 14 provided with a curved delivery-chute 15 leading from an opening in an overhang 16 of the main casing.

Pivoted at 17 in the upper extremity of the casing A is an oscillatory receiver 18 for the articles to be dispensed. In the present instance the receiver is adapted to contain cups C, which may be of paraffin-paper in the usual tapered form and with narrow flanges about their open ends. The 45 receiver may therefore be cylindrical or tubular with its lower end furnishing a de-

livery-opening. The cups may be introduced into the receiver through a removable cap 18^a, covering the top of the casing and suitably locked thereon. At this open end 5 and extending across the sides and front of the receiver is a slot or opening 19, and fixed to the walls 11 of the casing, projecting into the receiver through the slot, are opposite members 20, 20 having upper horizontal 55 surfaces 21 and lower cam or cup-withdrawing surfaces 22 inclined upwardly toward the front of the apparatus. These projections support a stack of cups in the normal vertical position of the receiver, said cups 60 being inverted and therefore excluding dust. The flange of the lower or terminal cup contacts at opposite points with the inner edges of the projections. The receiver is 65 yieldably held in its normal position by a spring 23 coöperating with pins 24 fixed to the casing and receiver.

The receiver may be moved from its vertical position to its opposite extreme of travel, against the tension of the spring, by 70 a finger-piece 25 extending from the receiver through a slot 26 in the casing. When the finger-piece is at the forward end of the slot the receiver lies within the protuberance 13. In this position the stack of 75 cups is supported by a shelf 27 extending just below the projections 20 in a position to enter the slot 19 as the receiver is swung forward. It will be noted that the projection surfaces 21 and 22 diverge from the 80 shelf. In the rearward position of the receiver its delivery-opening is over a temporary cup-support 28 at the bottom of the casing; then when the receiver is carried forward by the finger-piece the cup which 85 may have been resting upon this support will be slid over it and falls down the chute 90 15 upon what may be termed a dispensing support on the extension 14, where it may be readily secured by the user of the apparatus.

The dispensing of the cups may be under the control of a coin, for example, a cent, and for this purpose the following mechanism is well adapted. In the front plate 12 100 is a slot 30, from which leads a chute 31 terminating just above a coin-pocket 32

which is formed between the casing at 33 and a movable latch or retaining member 34. The latch is drawn into its coin-supporting position by a spring 35 extending between a point 36 on the casing and an arm 37 of the latch. Mounted upon the receiver adjacent to the coin-pocket and latch is a pawl 38 supported by a pin 39, and having its free end in the proper plane to 10 coöperate with a stop-shoulder 40 formed in the casing and which prevents forward delivery-movement of the receiver in the absence of a coin in the pocket. A pin 41 during the travel of the receiver contacts 15 with the rear end of the latch 34 to carry it away from the point 36 of the casing, thus widening the pocket to release the coin. When the coin leaves the pocket it enters a chute 42, which may direct it to a 20 suitable receptacle, not illustrated.

In the use of the apparatus, it will be considered that it has been previously operated, or that in some way a cup has already reached the temporary support 28. 25 This being the case, when a cent is placed in the slot 30 it falls into the pocket, and when the receiver is swung forward by the finger-piece 25 the pawl strikes the curved edge of the cent and is lifted out of engagement with the stop-shoulder. The movement of the receiver therefore continues, and its lower portion sweeps the cup from the support 28 into the chute and upon the dispensing support for removal by the pur- 30 chaser. As the receiver advances the pin 41 contacts with the latch to free and de- 35 posit the coin, as has been previously de- scribed. The finger-piece is now released, and the receiver returned to its initial posi- 40 tion by the spring 23. At its forward ex- treme of movement the stack of cups pass 45 beyond the projections 21 and onto the shelf 27, being lowered by the amount which this shelf is below the projections, and bringing the flanges of the terminal cup into a posi- 50 tion to coöperate with the cam surfaces 22. Therefore, upon the retraction of the receiver the lower cup is withdrawn by these cams and takes its place upon the support 55 28 ready for the next operation of the apparatus. At the same time the flanges of the next cup of the series pass above the pro- jections and rest upon the surfaces 21 to support the stack. When the projection 41 leaves the latch the spring 35 returns the latter to narrow the pocket so that it will support in its pawl-raising position the next cent introduced into the machine.

I claim and desire to secure by Letters Patent:

1. In dispensing apparatus, the combination of means for holding a stack of nested flanged cups, a stationary wedging device adapted to engage the flanges of adjacent

cups to separate the same and means for 65 moving the stack of cups into engagement with said wedging device.

2. In dispensing apparatus, the combination of means for holding a stack of nested flanged cups, stationary means having a 70 plurality of surfaces for engaging the cup flanges at a plurality of circumferentially-spaced positions and means for moving the cups to bring the flanges thereof into engagement with said surfaces. 75

3. In dispensing apparatus, the combination of means for holding a stack of nested flanged cups, a plurality of stationary wedging members adapted to enter between the flanges of adjacent cups at circumferentially-spaced positions, and means for moving the cups so as to bring the flanges thereof into engagement with the wedges and so separate the cups in a direction longitudi- 80 nal of the stack. 85

4. The combination with an article receiver mounted to move into either of two extreme positions, of means independent thereof for supporting the articles when the receiver is in one position, and means 90 independent of the receiver for supporting the articles within said receiver when the receiver is in the other position, the means for supporting the articles when the receiver is in the first position being adapted to co- 95 operate with the lowermost article to release the same from its supported position within the receiver in the transit of the receiver from the second to the first position.

5. The combination with an article-re- 100 ceiver mounted to move into different positions, of means operable in one position for withdrawing an article from the receiver and for supporting the withdrawn article, and means acting in another position of the 105 receiver to support the articles in said receiver and deliver the withdrawn article.

6. The combination with an article-re- 110 ceiver mounted to move into different posi- tions, of fixed means operable in one posi- 115 tion for withdrawing an article from the receiver and for supporting the withdrawn article, and means acting in another position of the receiver to support the articles in said receiver and deliver the withdrawn article.

7. The combination with an article-re- ceiver mounted to move into different posi- 120 tions, of fixed means operable in one posi- tion for withdrawing an article from the receiver and for supporting the withdrawn article, and independent fixed means acting in another position of the receiver to sup- port the articles in said receiver.

8. In a dispensing apparatus for paper cups, the combination with a cup container 1: adapted to hold a pile of nested cups in inverted position, said container being mov- ably mounted but having a lateral opening.

means independent of said container for supporting the cups in nested position when the container is in one position, and means independent of said container and of said 5 first-named supporting means for supporting the cups when the container is in its second position, said first-named supporting means being adapted to engage with the lowermost of said cups and release the same 10 from the pile of nested cups coincident with the movement of the container from its second position to its first position.

9. The combination with a casing, of an article-receiver movable therein, and means 15 carried by the casing for supporting the articles in the receiver, said supporting means being provided with means for withdrawing articles from the receiver, and independent article-supporting means fixed to the 20 casing.

10. The combination with a tubular article-receiver movably mounted and being provided with a lateral opening, of a plurality of article-supporting means entering 25 the opening in different positions of the receiver, one of said supporting means having cam-surfaces for engagement with the articles.

11. In dispensing apparatus, the combination of means for holding a stack of nested 30 cups, stationary means for loosening a terminal cup from the stack to permit the same to drop away from the stack by gravity and means for moving said terminal cup 35 into operative engagement with said stationary loosening means.

12. In dispensing apparatus, the combination of means for holding a stack of nested 40 cups, stationary means for separating a terminal cup from the stack and means for moving said stack to bring a cup to be separated into engagement with said stationary 45 separating means.

13. In a dispensing apparatus, the combination with a casing, of a receiving tube 45 movable therein and being provided with a delivery-opening, opposite projections over which the delivery-opening passes in one portion of its travel, and a shelf fixed to the 50 casing and coöperating with the opening in another portion of the travel.

14. In a dispensing apparatus, the combination with a casing, of a receiving tube 55 movable therein and being provided with an independent delivery-opening, opposite projections over which the delivery-opening passes in one portion of its travel, and a shelf fixed to the casing and coöperating with the opening in another portion of the travel, the 60 opposite edges of the projections diverging from the shelf.

15. The combination with a casing, of a tube movable therein and being provided with a slot in its wall, and opposite projec-

tions and a shelf carried by the casing and coöperating with the slot, the projections being adapted to engage articles in the casing and to draw said articles between them.

16. The combination with a casing, of an article-receiving tube movable therein and 70 being provided with a slot in its side wall, opposite projections and a shelf carried by the casing and coöperating with the slot, a temporary support for each article delivered from the tube, and a dispensing support to 75 which the article passes from the temporary support.

17. The combination with a casing, of an article-receiving tube movable therein and being provided with a slot in its side wall, 80 opposite projections along which the casing-slot passes in one portion of its travel, a shelf fixed to the casing and entering the slot in another portion of the travel, a temporary article-support situated below the 85 projections, and a support situated below the shelf.

18. In dispensing apparatus, the combination of means for holding a stack of nested cups, stationary means for separating a terminal cup from the stack and permitting the same to drop away from the stack by gravity, means for moving the stack of cups to cause said separating means to separate a cup from the stack, a stationary support 95 to receive the cup separated by said separating means and means for discharging said cup from said support.

19. In dispensing apparatus, the combination of means for holding a stack of nested 100 cups, stationary means for separating a terminal cup from the stack, means for moving the stack of cups to bring a terminal cup into operative engagement with said separating means to separate the cup and permit 105 the same to drop away from the stack by gravity, a support to receive said separated cup and means associated with said stack-moving means for discharging the separated cup from said support.

20. In dispensing apparatus, the combination of means for holding a stack of nested cups, stationary means for separating a cup from the stack and supporting the remainder of the stack while the separated cup drops 115 away from the same by gravity, a support to receive said separated cup, said stack of cups being movable in one direction to cause said separating means to separate a terminal cup therefrom, and being movable in the other 120 direction to place the stack in condition for another operation of said cup-separating means, and means associated with said stack-moving means for discharging the cups from said support when said stack is moved 125 away from said cup-separating means.

21. In dispensing apparatus, the combination of laterally movable means for holding

a stack of nested cups, and stationary means adapted to be engaged by the cups when moved laterally for effecting relative movement between the cup stack and a terminal cup in a direction longitudinal of the cup stack to free the terminal cup from the stack.

Signed at New York, (borough of Manhattan), in the county and State of New York, this 14 day of December, 1909.

WILLIAM MILLARD.
